DESIGN FOR AN EMBROIDERED FABRIC

Albert Ruchman, New York, N. Y.

Application January 17, 1938, Serial No. 74,364

Term of patent 3½ years

To all whom it may concern:

Be it known that I, Albert Ruchman, a citizen of the United States of America, residing in New York city, in the Borough of Manhattan, county and State of New York, have invented a new, original, and ornamental Design for an Embroidered Fabric, of which the following is a specification, reference being had to the accompanying drawing, forming part thereof, wherein,

The figure is a plan view of a piece of embroidered fabric showing my new design between the two selvage edges of the fabric.

I claim:

The ornamental design for an embroidered fabric, substantially as shown, and described.

ALBERT RUCHMAN.
